ROCKER ARM RESURFACING MACHINE

Leonard L. Talbott and Frank G. Laidlaw,
Reno, Nev.

Application May 2, 1952, Serial No. 285,587

2 Claims. (Cl. 51—56)

1

This invention relates to grinding machines, and more particularly to a machine for use in resurfacing valve rocker arms of internal combustion engines.

The main object of the invention is to provide a novel and improved rocker arm resurfacing machine which is simple in construction, which is easy to operate, and which is adjustable to accommodate a wide range of sizes of valve rocker arm assemblies for the resurfacing of the faces thereof.

A further object of the invention is to provide an improved machine for resurfacing the faces of valve rocker arms of internal combustion engines, the improved machine being inexpensive to manufacture, being sturdy in construction, and being arranged to provide grinding of the rocker arm faces to the necessary curved surfaces recommended by automobile manufacturers for best operation of the rocker arms.

Further objects and advantages of the invention will become apparent from the following description and claims, and from the accompanying drawings, wherein:

Figure 1 is a side elevational view of an improved rocker arm resurfacing machine constructed in accordance with the present invention, showing a conventional rocker arm assembly mounted therein in position for resurfacing.

Figure 2 is a top plan view of the structure shown in Figure 1.

Figure 3 is an enlarged end elevational view of the structure shown in Figures 1 and 2.

Figure 4 is an enlarged transverse vertical cross sectional view taken on the line 4—4 of Figure 1.

Figure 5 is a cross sectional detail view taken on the line 5—5 of Figure 4.

Referring to the drawings, the improved rocker arm resurfacing machine is designated generally at 10 and comprises a pair of elongated parallel rods 11 and 12 rigidly connected at one end by a transverse, vertical plate member 13 and rigidly connected at their opposite ends by an upstanding transverse vertical plate member 14. The plate member 14 is formed at its forward portion with the vertical arm 15 in the upper portion of which is secured an inwardly directed stud element 16 having a tapered point 17. Designated at 18 is a transversely extending upstanding vertical plate member generally similar in shape to the plate member 14 and formed with the vertical upstanding arm 19 at its forward portion. The plate member 18 is rigidly

secured to respective sleeve members 20 and 21 which are slidably mounted on the respective rods 12 and 11, the sleeve member 20 being formed with the clamping portion 22 having the opposed parallel lugs 23 and 24. Designated at 25 is a clamping screw which extends through the lug 24 and is threadedly engaged with the lug 23, whereby the portion 22 may be tightly clamped to the rod 12 by tightening the screw 25, thus locking the plate member 18 in an adjusted position on the rods 11 and 12.

The arm 19 has secured thereto the inwardly extending stud element 26 which is in alignment with and opposes the stud element 16, the stud element 26 being formed with the tapered point 27 which is in longitudinal alignment with and opposes the tapered point 17 of stud element 16.

As shown in Figure 1, the stud elements 16 and 26 are adapted to engage in the ends of the shaft 28 of a conventional rocker arm assembly 29 to support said rocker arm assembly in parallel relationship to the rods 11 and 12 and in a position elevated above the plane of said rods.

Designated respectively at 30 and 31 are respective sleeve members slidably engaged on the rods 12 and 11 and having welded thereto the upstanding, parallel plate members 32 and 33 which are rigidly connected by the respective transversely extending rod members 34 and 35, said rod members 34 and 35 being located substantially at the opposite top corners of the plate members 32 and 33. The sleeve members 30 and 31, the plate members 32 and 33, and the rods 34 and 35 thus define a rigid bracket member which is slidable longitudinally on the rods 11 and 12.

Slidably mounted on the rod members 34 and 35 are the respective sleeves 36 and 37 to which is rigidly secured a plate member 38. Welded on the plate member 38 and extending transversely to the rods 12 and 11 are the parallel, inverted angle bars 39 and 40 which have secured to their outer top portions the respective arcuate clamping straps 41 and 42. The straps 41 and 42 terminate in the respective upstanding apertured lugs 43 and 44 through which extends a clamping bolt 45. Designated at 46 is an electric motor which is clampingly secured on the angle bars 39 and 40 by the clamping straps 41 and 42, as shown in Figures 3, 4 and 5. The shaft of the motor extends transversely with respect to the rods 11 and 12 and has mounted on its end the grinding wheel 47. Designated respectively at 48, 49 are coiled springs surround-

ing the rods 34 and 35 and biasing the sleeve members 36 and 37 toward the vertical longitudinal plane containing the axis defined by the stud elements 16 and 26.

Secured to the forward peripheral portion of the motor casing is the guard disc 49 which covers the upper portion of the grinding wheel 47 and which is formed with a relatively large V-shaped notch 50 at its lower portion, allowing a rocker arm to be rotated into engagement with the lower portion of the front face of the grinding wheel 47, as is clearly shown in Figure 1.

In using the device, the rocker arm assembly 29 is mounted in the manner shown in Figure 1, with the ends of the rocker arm shaft 28 engaging and supported by the stud elements 16 and 26, the plate member 18 being locked in a position wherein its stud element 26 supportingly engages the end of the rocker arm shaft 28 by tightening the clamping screw 25. As shown in Figure 1, the rocker arm faces may then be successively rotated into engagement with the grinding wheel 47, the motor 46 being energized to rotate said grinding wheel. The rocker arm faces may then be successively resurfaced, the rocker arms being rotatable and the grinding wheel being yieldable rearwardly against the biasing force of the springs 48, 49, to allow the rocker arm faces to be correctly shaped.

It will be readily apparent that the bracket means defined by the plate member 18 and its supporting sleeves 20 and 21 is readily adjustable longitudinally on the rails 11 and 12 to accommodate rocker arm assemblies 29 of different lengths.

While a specific embodiment of an improved resurfacing machine for rocker arms of internal combustion engines has been disclosed in the foregoing description, it will be understood that various modifications within the spirit of the invention may occur to those skilled in the art. Therefore, it is intended that no limitations be placed in the invention except as defined by the scope of the appended claims.

What is claimed is:

1. A machine for refacing rocker arms of an internal combustion engine comprising a pair of parallel guide rails, means rigidly connecting the ends of the rails, including an upstanding support member, a first stud element on said support member extending parallel to said rails, a first upstanding bracket slidably mounted on said rails, a second stud element on said bracket in alignment with and opposing the first stud element and defining therewith means for rotatably supporting the shaft of a rocker arm assembly in parallelism with said rails, a second upstanding bracket slidably mounted on said rails, an electric motor, means slidably supporting said motor on said last-named bracket for movement at right

angles to the rails, spring means biasing said motor toward the vertical plane of the stud elements, said motor being mounted with its shaft extending transverse to the rails, and a grinding wheel secured to the motor shaft, said grinding wheel being engaged and moved rearwardly against the bias of said spring means on rotation of said rocker arm, whereby to grind said rocker arm to the desired curvature.

5 2. A machine for refacing rocker arms of an internal combustion engine comprising a pair of parallel guide rails, means rigidly connecting the ends of the rails, including an upstanding support member, a first stud element on said support member extending parallel to said rails, a first upstanding bracket slidably mounted on said rails, a second stud element on said bracket in alignment with and opposing the first stud element and defining therewith means for rotatably supporting the shaft of a rocker arm assembly in parallelism with said rails, means releasably locking said bracket with respect to said rails, a second upstanding bracket slidably mounted on said rails, an electric motor, means slidably supporting said motor on said second bracket for movement at right angles to the rails, spring means biasing said motor toward the vertical plane of the stud elements, said motor being mounted with its shaft extending transverse to the rails, a grinding wheel secured to the motor shaft, and a guard disc secured to said motor and covering the upper portion of said grinding wheel, the guard disc having a relatively large V-shaped notch in its lower portion, thereby allowing a rocker arm to be rotated into engagement with the lower portion of the grinding wheel, said grinding wheel being moved rearwardly against the bias of said spring means on continued rotation of said rocker arm, whereby to shape said rocker arm to the desired curvature.
